UNITED STATES PATENT OFFICE.

FREDERIC C. MACKEY AND JOHANN H. GUMZ, OF CHICAGO, ILLINOIS.

ENAMELING FURNACE.

Application filed March 20, 1922. Serial No. 545,159.

To all whom it may concern:

Be it known that we, FREDERIC C. MACKEY and JOHANN H. GUMZ, both citizens of the United States, and residents of Chicago, 5 county of Cook, and State of Illinois, have invented certain new and useful Improvements in Enameling Furnaces, of which the following is a specification.

Our invention relates generally to improvements in enameling furnaces, but relates more particularly to improvements in furnaces used in the production or manufacture of vitreous enamel ware in which exceedingly high temperatures are required.

15 The general object of our invention is to provide a vitreous enameling furnace where- with a given amount of enamel ware can be produced with the consumption of less fuel.

Again it is an object of our invention to 20 provide a vitreous enameling furnace where- with a given amount of work or material can be enameled in less time, in less space, and at less cost than is possible with furnaces heretofore devised.

25 It is also an object of our invention to provide a vitreous enameling furnace of such construction that it will be better adapted to withstand the extremely high temperatures obtaining in such furnaces, to the end that the cost of maintenance may be reduced and the periods of continued or uninterrupted service increased.

Again with respect to the production of work of certain kinds, it is an object of our 35 invention to provide a furnace wherewith a given amount of material can be produced or enameled in a furnace of a size much smaller than that required to perform a like amount of work in furnaces heretofore devised.

40 Our invention consists generally in a furnace of the form, arrangement, construction, proportion, and co-operation of the parts whereby the above named objects, together with others that will appear hereinafter, are attainable; and our invention will be more readily understood by reference to the accompanying drawings which illustrate what we consider, at the present time, to be the 45 preferred embodiment thereof.

In said drawings:

Fig. 1 is a longitudinal vertical section of 50 a furnace embodying our invention viewed substantially along the line 1—1 of Figs. 2 and 3.

Fig. 2 is a transverse vertical section substantially along the line 2—2 of Fig. 1.

Fig. 3 is a transverse longitudinal section substantially on the line 3—3 of Fig. 2, and Fig. 4 is a detail sectional view descriptive 60 of the operation of the furnace as affecting the fire brick or lining thereof.

While the drawings are not accurately drawn to scale they are approximately drawn to the scale of $\frac{3}{4}$ inches to one foot from 65 which the proportions will be more readily ascertainable.

While the furnace shown in the drawings is a gas fired furnace, liquid or other fluids may be employed so that the showing herein 70 should be taken as by way of illustration and not by way of limitation.

The size of the furnace, of course, may be varied, but there are certain relative proportions that we deem advisable and even necessary to maintain, the factors controlling 75 which will be developed in the detail description hereinafter given.

As will be observed, the furnace is of 80 elongated form and is composed of vertical outer side walls 1 and 2 and vertical end walls 3 and 4. These walls may be made of various materials, but are usually made of a non-fire brick, such for example, as red brick. Within the outer walls will be found an intermediate filling, usually of an insulating brick, to which the reference character 5 has been applied.

The combustion space of the furnace proper is defined by the fire brick lining 90 which is formed to present vertical side walls 6 and 7 and an end wall 8. The other end of the furnace is provided with an opening 9 to permit placement of the work in and removal thereof from the furnace, this opening being closed by a door or gate 10 which is provided with an inner fire brick lining 11. The top of the furnace 12 is formed in the shape of an arch in order to span the distance between the side walls, and in order 100 to present a structure adapted to sustain itself even under the high temperatures prevailing in the furnace.

As before stated, the furnace under consideration is fired by gas and for this purpose there is provided a plurality of burners 13 on one side of the furnace, and a plurality of burners 14 upon the other side, the burners 14 being staggered or offset with 105 relation to the burners 13. As is well shown, 110

the burners 13 and 14 are provided with inwardly extending nozzle portions 13' and 14', respectively, which terminate in and discharge into openings 15 and 16, respectively, in the fire brick side walls 6 and 7.

Upstanding from the bottom or floor 17 we have formed a plurality of longitudinally extending piers 18, 19, 20, 21 and 22, which extend from end to end of the furnace. These 10 piers are provided with transverse openings 18', 19', 20', 21', and 22', respectively, which are alined with the nozzles 13' and 14' of the fuel burners so that the flames projected by or from the burners can go forward freely 15 under the natural burning action thereof.

By the novel shaping and positioning of the piers 18 to 22, inclusive, we are able, in a given size furnace, to provide more piers than can normally be provided under the 20 practice heretofore prevailing. As a result, we are able to secure several distinct and important advantages. As will be observed, the various piers, as here shown, are all of substantially the same width, but the spaces 25 between the piers 18 and 19, on the one hand, and 21 and 22 on the other hand, are greater than the spaces between the group of piers 19, 20, and 21. It will also be observed that as shown the piers 18 and 22 30 are spaced from the side walls a distance substantially equal to the distance between the respective piers of the middle group 19, 20, and 21. This larger number of piers, obviously, provides a larger surface area for 35 exposure to the heat or products of combustion within the furnace chamber, the advantageous characteristics of which will be more fully developed hereinafter.

The work or material to be enameled is 40 usually placed into the furnace by means of a device known in the trade as a loading fork. In order that the work may be properly supported as it is conveyed into the furnace, this loading fork must be of considerable width and by the spacing of the piers 18 and 19, and 21 and 22, as shown, we are 45 able to accommodate the forks even with the larger number of piers provided. The larger number of piers also provides support for 50 the work at a larger number of points, thus eliminating danger of sagging which is quite likely to occur in other furnaces, particularly where large pieces are being treated.

The side walls, the top, and the bottom of 55 the furnace have been treated in a novel manner whereby we have provided an enormous surface relative to the cubical capacity or size of the furnace. At this point, it might be well to recall to mind certain of the 60 objects of our invention, to wit, the object of treating or enameling a given amount of work with less fuel, and the object of providing a furnace construction, which shall minimize those destructive forces or reactions 65 that cause premature or early disintegra-

tion of the walls of the furnaces that are subjected to the extremely high temperatures required for vitreous enameling operations. These objects we attain by virtue of the various novel structural characteristics of our 70 furnace, the value of which is increased when operated in the manner in which we shall now describe.

Before entering upon a description of the operation of the furnace, attention is directed to the large number of pockets 23 that are formed in the side walls, ends, bottom or floor, and top of the furnace. These pockets are formed by staggering the bricks that form the lining of the furnace, both 75 with respect to the superposed layers or courses and with respect to the innermost plane of the furnace walls. In this manner, an enormous surface is presented to the products of combustion in the furnace, 80 whereby the products of combustion are caused to give off a far greater part of their heat before discharging through the outlets 85 25 in the top wall or arch 12, than is the case in furnaces heretofore devised. 90

In the furnace disclosed there are at least 1000 square inches of surface to every square foot of area in the plane parallel to the bottom, i. e., in the area available for the work to be enameled. While the drawings show the furnace as having only a curved upper wall and straight sides and bottom walls, they may all be curved so that the terms top, bottom and side walls in the claims 95 should be considered as referring broadly 100 to such general portions of the furnace.

In operation, assuming that the furnace has previously been brought to working temperature and that the furnace is empty, i. e. 105 the work previously enameled has been removed, the burners 14 and 15 are turned on, thus producing an intense burning mass within the furnace. The length of time that the burners operate will vary somewhat, depending upon the amount of work being treated, but because of our novel construction the period of operation of the burners 110 can be considerably reduced with the obvious result that less fuel is required. The 115 reason why less fuel is required may not at first be apparent, nor will it, at first thought, be obvious that any other improved result follows from this lesser period of operation and the smaller fuel consumption. These 120 characteristics, however, do result from our construction for reasons which we shall now develop.

The burners operate approximately only 125 for a period of from forty to fifty seconds in which short time, the heat generated is absorbed in a very efficient manner by the enormous surface exposed to the products of combustion. Because of the extremely short period of firing and the enormous surface of 130 the furnace walls (relative to the cubical

capacity of the furnace), the fire brick is enabled to and does absorb a far greater percentage of the heat units and, at the same time, this heat does not penetrate as deeply 5 into the walls of the furnace, thus providing a zone of increased temperature that is relatively close to the surface of the furnace wall, as indicated by the shaded portion 26 in the descriptive view (Fig. 4). The heat units 10 are thus in a condition or position where they can be more readily given off to the work when it is placed within the furnace. That is to say, if the same amount of heat were stored in the furnace walls of the usual 15 flat sided construction that penetration of the heat would extend much further into the fire brick, because it would be necessary to raise the walls through a much greater number of degrees of temperature in order to 20 store the same number of heat units. When deep penetration exists, it is obvious that the heat cannot be as quickly and efficiently given off to the work. It should also be obvious that the furnace wall cannot be 25 raised through a wide temperature change as efficiently as it can be through a relatively low temperature change. Thus we secure both the advantage of confining the heat to what may be termed a surface zone 30 and, at the same time, the advantage of a more efficient absorption of the heat generated by the burning fuel. We also secure further important advantages far and above those already stated in that the walls, as a 35 whole, are not raised to as high a temperature, with the result that they are able to stand up in use for longer periods of time, and what is probably of even greater importance, the difference in temperature between 40 the furnace walls at the time when they have absorbed the heat prior to the placement of the work in the furnace, and the condition thereof after they have given off their heat to the work, is far less than in 45 furnaces heretofore devised. We thereby eliminate one of the most destructive forces operating to destroy or cause disintegration of fire brick, to wit, rapid and great changes in the temperature of the fire brick. The 50 practical result of this, of course, is that our furnace may be operated for longer periods without attention or repair, which is an important advantage when it is considered that 55 enameling furnaces are usually operated continuously, i. e. twenty-four hours per day.

While it cannot be stated with accuracy, the length of time that the work must remain in the furnace, this will only be for a period of several minutes, and it should 60 be obvious that with our construction the work need not remain as long in the furnace as would otherwise be required. Thus, the operations of enameling are speeded up as well as produced at less cost in fuel outlay 65 and furnace maintenance.

The many advantages of our furnace will now be apparent to those skilled in this art without further comment.

We claim:

1. An enameling furnace embodying therein a refractory lining formed with a checkered surface, as and for the purpose specified.
2. An enameling furnace embodying therein a chamber having side walls and top and bottom walls, said side walls having a plurality of recesses therein.
3. An enameling furnace embodying therein a chamber having side walls and top and bottom walls, said side walls and top having a plurality of recesses therein.
4. An enameling furnace embodying therein a chamber having side walls and top and bottom walls, said side walls, top and bottom having a plurality of recesses therein.
5. An enameling furnace embodying therein side walls, top, bottom and end walls, said walls all having a plurality of recesses therein.
6. An enameling furnace embodying therein a chamber having side walls and top and bottom walls, said side walls having a plurality of pockets therein.
7. An enameling furnace embodying therein a chamber having side walls and top and bottom walls, said side walls and top having a plurality of pockets therein.
8. An enameling furnace embodying therein a chamber having side walls and top and bottom walls, said side walls, top and bottom having a plurality of pockets therein.
9. An enameling furnace embodying therein side walls, top, bottom and end walls, said walls all having a plurality of pockets therein.
10. An enameling furnace embodying therein a chamber having side walls and top and bottom walls, said side walls having a plurality of pockets therein, said pockets being formed by courses of firebrick, alternate bricks of every row being spaced inwardly with respect to the others, and the innermost bricks of adjacent courses being offset with respect to those of the first mentioned course.
11. An enameling furnace embodying therein a chamber having side walls and top and bottom walls, said side walls and top having a plurality of pockets therein, said pockets being formed by courses of firebrick, alternate bricks of every row being spaced inwardly with respect to the others, and the innermost bricks of adjacent courses being offset with respect to those of the first mentioned course.
12. An enameling furnace embodying therein a chamber having side walls and top and bottom walls, said side walls, top

- and bottom having a plurality of pockets therein, said pockets being formed by courses of firebrick, alternate bricks of every row being spaced inwardly with respect to the others, and the innermost bricks of adjacent courses being offset with respect to those of the first mentioned course. 16. An enameling furnace having a chamber provided with a bottom wall, a plurality of longitudinally disposed transversely spaced piers upstanding therefrom, 35 said piers including a centrally disposed group, the piers of which are spaced a lesser distance apart than other of the piers and a plurality of recesses formed in the bottom between the said piers. 40
13. An enameling furnace embodying therein side walls, top, bottom and end walls, 10 said walls all having a plurality of pockets therein, said pockets being formed by courses of firebrick, alternate bricks of every row being spaced inwardly with respect to the others, and the innermost bricks of adjacent courses being offset with respect to those of the first mentioned courses. 17. An enameling furnace having a chamber provided with a bottom wall, a plurality of longitudinally disposed transversely spaced piers upstanding therefrom, 45 said piers including a group of three centrally disposed piers, the respective piers of which are spaced a lesser distance apart than other of the piers, and a plurality of recesses formed in the bottom between the said piers. 50
14. An enameling furnace having a chamber provided with a bottom wall, a plurality of longitudinally disposed transversely spaced piers therein, said piers including a centrally disposed group, the piers of which are spaced a lesser distance apart than other of the piers. 18. The method of enameling that consists in providing a furnace having a chamber, the walls of which are formed to expose at least 1000 square inches of surface to every square foot of area in a plane 55 parallel to the bottom, i. e. in the area available for the work to be enameled. 50
15. An enameling furnace having a chamber provided with a bottom wall, a plurality of longitudinally disposed transversely spaced piers therein, said piers including a group of three centrally disposed piers, the respective piers of which are spaced a lesser distance apart than other of the piers. In testimony whereof, we have hereunto set our hands, this 9th day of March, 1922.
- FREDERIC C. MACKEY,
JOHANN H. GUMZ
